(57) **CLAIM**

The ornamental design for a charging case for wireless earphones as shown and described.

DESCRIPTION

FIG. 1 is a front view of a charging case for wireless earphones showing the new design;

FIG. 2 is a back view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is a perspective view thereof; and,

FIG. 9 is a perspective view of the charging case for wireless earphones of FIG. 1 shown in an alternate position.

Broken lines depict portions of the charging case for wireless earphones that form no part of the claimed design.

1 Claim, 9 Drawing Sheets
